UNITED STATES PATENT OFFICE.

MARTIN GEBHARDT, OF NEW YORK, N. Y.

DESIGN FOR A RING.

SPECIFICATION forming part of Design No. 29,353, dated September 20, 1898.

Application filed August 12, 1898. Serial No. 688,454. Term of patent 7 years.

To all whom it may concern:

Be it known that I, MARTIN GEBHARDT, of the city of New York, borough of Brooklyn, and State of New York, have invented and produced a certain new and original Design for Rings, of which the following is a full, clear, and exact description, reference being had to the accompanying drawings, wherein—

Figure 1 is a side elevation of a ring embodying my newly-invented design; and Fig. 2, a plan view, on enlarged scale, showing a full design.

The characteristic features of my design reside in the ornamental shaping of the head of the ring, in the combination of artistic curves surrounding the head, and in the ornamental configuration of such scrolls, combined with the representation of a flower connecting both sides of the head to the band of the ring.

The head *a* of the ring is oval, and its longitudinal apexes are extended in scrolls *b* oppositely to correspondingly-shaped scrolls *c*, set within the area of the head. The heads of scrolls *b* are full, whereas the heads of scrolls *c* are provided with correspondingly-shaped indentions *d*. The edges of the incisions surrounding the scrolls are curved and extended into spars *e*.

The head *a* of the ring is raised above the plane of the ring and appears to rest on the radially-arranged scrolls *f*, which are formed similarly to scrolls *b*. The heads of these scrolls *f* are joined by curves *g*, and together with these form the outline of the ornament surrounding the head of the ring.

The part of the ornament joining the head to the band of the ring is composed of two

combined helical scrolls *h*, placed with their backs toward each other, an Ionic scroll *j* terminating the ornament toward the band and facing the field between the two helical scrolls *h*, and of an ornamental flower *p*, set in the field between the Ionic scroll and the helical scrolls.

The flower *p* springs from the center of the Ionic scroll *j* and reaches approximately midway between the double helical scrolls *h*, and two heart-shaped leaves *l* are set one on each side of the stem of the flower. In the joining-points of the helical scrolls *h* are set butts *i* and joined to the heads of the scrolls by concave curves *g*. Similar curves join the helical scrolls to the scrolls or volutes *f* and also to the Ionic scrolls *j*, thus completing the outlines of the ornament.

The ground between the ornamental curves is matted. The sides of the ornamental curves are smoothly finished and the edges of the scrolls *f* are scalloped.

The setting for the stone in the head *a* of the ring is shown in the drawings in the form of an octagon star, four points thereof being sharp and four rounded.

I claim as my invention—

The design for a ring as herein shown and described.

In witness that I claim the design described in the foregoing specification I have signed my name in the presence of two subscribing witnesses.

MARTIN GEBHARDT.
